United States Patent Office

Des. 178,924
Patented Oct. 9, 1956

178,924

WRITING INSTRUMENT

David Kahn, Englewood, N. J., assignor to David Kahn, Inc., North Bergen, N. J., a corporation of New Jersey

Application September 12, 1952, Serial No. 21,438

Term of patent 14 years

(Cl. D74—17)

Fig. 1

Fig. 2

Fig. 3

Fig. 4

Fig. 1 is a front elevational view of the writing instrument with the writing element in a retracted position;

Fig. 2 is a side elevational view of the writing instrument as shown in Fig. 1, with the writing element in retracted position;

Fig. 3 is a side elevational view of the writing instrument with the writing element in a projected position; and

Fig. 4 is a top view of the writing instrument.

The horizontal shade lines appearing upon the lower portion of the barrel, the intermediate band and the push button are for the purpose of noting a uniform color in sharp contrast to the balance of the pen.

I claim:

The ornamental design for a writing instrument, substantially as shown and described.
